EDWIN J. PRINDLE, OF EAST ORANGE, NEW JERSEY, ASSIGNOR, BY MESNE ASSIGNMENTS, TO FITZ-EMPIRE DOUBLE PIVOT LAST COMPANY, OF AUBURN, MAINE, A CORPORATION OF MAINE.

GRADING MECHANISM, A SCALE AND METHOD OF FORMING SAID SCALE FOR LAST-TURNING LATHES.

1,334,400.

Specification of Letters Patent. Patented Mar. 23, 1920.

Application filed April 25, 1918. Serial No. 230,621.

To all whom it may concern:

Be it known that I, EDWIN J. PRINDLE, of East Orange, in the county of Essex, and in the State of New Jersey, have invented a certain new and useful Improvement in Grading Mechanism, Scales and Methods of Forming Said Scales for Last-Turning Lathes, and do hereby declare that the following is a full, clear, and exact description thereof.

10 This invention relates to grading mechanisms used in pattern copying machines, and is disclosed as embodied in a last lathe.

15 The essential parts of a pattern copying machine are four supporting instrumentalities, which need not all be movable, for the tracing point or model wheel, the tool, the model and the work, respectively, and grading mechanisms for regulating the relative movements of these instrumentalities to 20 make the relative movement of the tool and work geometrically or pantographically related to that of the tracing point and model in one or more dimensions.

25 In the grading of lasts, the successive settings of the length grading mechanism, while simply arithmetically related as far as any one model is concerned, are not the same for the same sizes graded for different models. This is because lasts of the same marked size are not of the same length, owing to differences in style, and the successive sizes differ in length by a constant arbitrary length unit, as $\frac{1}{3}$ inch, regardless 30 of the actual length of the model. For example, if the model 7 is 11 inches long, the 35 8, 9 and 10 are $11\frac{1}{3}$, $11\frac{2}{3}$ and 12 inches long respectively, and the corresponding magnification ratios are

40 $\frac{34}{33}, \frac{35}{33}, \frac{36}{33}$

while if the model 7 is $11\frac{1}{3}$ inches long, the corresponding ratios are

45 $\frac{35}{34}, \frac{36}{34}, \frac{37}{34}$

The difficulty of making the grader set-

ting in such a system is obvious. In practice in machines as heretofore constructed, this difficulty has been dealt with by a somewhat clumsy and unsatisfactory construction. These machines had a single unit 50 uniformly graduated length-grading scale which was used to grade from any model 55 by changing the vertical position of the lower grading lever pivot, in correspondence with the model length, thus changing the advantage of the lever so that the grading scale would work with it to produce successive increments of $\frac{1}{3}$ inch in the lasts cut. It is advisable also, in machines of this type, to keep the lower pivot opposite the center of the model, and the two objects were attained by moving the pivot along a sloping 60 bar which would position the pivot at the proper vertical elevation when it was under the model center. While this construction is capable of good work, it was hard to set accurately, and in consequence there was 65 more or less "jockeying" with the adjustments at the lower pivot point and at the scale. The setting of the lower pivot was 70 also a fruitful source of error, as the absolute length of the model last would never 75 in practice have any value simply expressible in inches, or in size notation.

It is the object of the present invention to avoid these and other difficulties and to provide a grading mechanism which will be 80 simple in adjustment and accurate in use.

Accordingly an important feature of the invention resides in a novel organization comprising a universal chart of grading scales continuously in operative relation to 85 an adjustable member of the grading mechanism, for setting this member to any desired grade from any length of model.

Another feature of the invention is the solution of the problem of keeping the lower 90 lever pivot opposite the model center. The necessity of raising and lowering this pivot with its entailed difficulty of accurate adjustment and loss of time has been avoided 95 by the provision of the universal grading scale, and it is only necessary that it be

moved laterally. The present invention provides a mechanical model measuring means for setting the pivot accurately opposite the center of the model.

5 The above remarks will be better understood by reference to the following description of a preferred embodiment of the invention, selected for purposes of illustration and shown in the drawings in which:—

10 Figure 1 is a front elevation of the machine;

Fig. 2 is an enlarged detail of the grading mechanism;

15 Fig. 3 is a section on the line 3—3 of Fig. 2;

Fig. 4 is a section on the line 4—4 of Fig. 2;

Fig. 5 is a side view of the parts shown in Fig. 2;

20 Fig. 6 is a section on the line 6—6 of Fig. 2;

Fig. 7 is a section on the line 7—7 of Fig. 2;

Fig. 8 is a detail.

25 Fig. 9 is a developed view of the scale.

Fig. 10 is a diagram illustrating the grading mechanism.

While my invention is capable of embodiment in many different forms, I have illustrated it by the best embodiment thereof known to me, and such embodiment is to be regarded only as typical of many possible embodiments, and my invention is not to be confined to the illustrated embodiment.

30 35 In the illustrated embodiment, the invention is shown as applied to an ordinary Blanchard, or last-turning lathe. The lathe consists essentially of the usual bed 1, supported upon legs, the bed having upon it a model-wheel carriage 2 carrying a model wheel 3, and a cutter carriage 4 in pillars upon which a cutter head 5 is mounted, the cutter head, when revolving, making a solid of revolution usually of the same size as the model wheel. The model-wheel carriage

40 45 and the cutter carriage are mounted on a guide 6 on the bed, and one of them (usually the cutter carriage) is moved along with the guide by power, and motion is transmitted from such carriage to the model-wheel carriage through grading mechanism, as will be more fully described later. From the

50 55 table rise stationary side frames 7 and 8, which at their upper ends support a shaft 9 on which is hung a swing frame consisting of end frames 10 and 11, carrying guide bars 12 and 13. The guide bars 12 and 13, like the ways of an ordinary turning lathe, carry a head stock in which is mounted a

60 65 model head stock spindle and a heel dog 14, and a model tail stock 15 carrying a toe dog 16 for the model last, which is to be used as a model in reproducing the new last desired. The guide bars 12 and 13 also carry

65 70 a block head stock 17, with its heel dog 18,

and a block tail stock 19, with its toe dog 20, that are to support the rough block from which the last is to be formed.

In the operation of the lathe, the weight of the swinging frame normally draws the latter toward the model wheel until the model last rests against the model wheel. As the model revolves, it swings the swing frame back and forth so that the cutter head cuts out of the block or blank a new last which is the same shape in cross-section as the old one. The carriages of the model wheel and cutter head are caused to travel lengthwise of the main frame, so that all parts of the model surface are presented to the model wheel and the corresponding parts of the new last are shaped.

In order to obtain a new last of the desired longer or shorter size than the model, a grading mechanism is used to transmit motion of the model carriage from the cutter carriage along the guide 6, which is usually greater or less than that of the cutter carriage, according to the result desired. The mechanism which I have shown for this purpose consists of a grade bar 21 which is swiveled on the model-wheel carriage 2, as by a tapered pin 22 that is journaled in a corresponding socket in the model carriage, and is secured therein by lock nuts 23. The lower end of the grade bar, as shown, swings and slides on a pin 24 on a slide 25 that is mounted in a slideway formed by guides 26 and 27 in a base plate 28. The grade bar has a slot 29, the walls of which engage the pin 24 and thus the grade bar is carried by, and turns upon, the pin 22 on the model carriage, while it turns and slides upon the pin 24. Means for moving the slide 25 in its slideway is shown and, in the present instance, it consists of a screw shaft 30 which is mounted in bearings on the ends of the plate 28, such shaft having a thread 30^a which engages the slide 25.

70 75 80 85 90 95 100 105 110 115 120 125 130 In the same slideway as the slide 25 is mounted a slide 31 carrying a plate 32 perpendicular to the slideway, the slide 31 being moved by a screw thread 33 on the same shaft as the screw thread 30^a, the pitch of the screw 33 being twice as great as that of the thread 30^a for a reason to be explained later. A shelf or plate 34 is fastened to the plate 28 so as to support a model last, as shown in dotted lines, there being a heel plate 35 against which the heel of the last may be rested. A hand wheel 36 is provided for turning the screw shaft to draw the plate 32 against the toe of the model, and to position the pin 24 on which the grade bar swings, as will be more fully described later. The grade bar has a guideway 37 extending above and below its fulcrum pin 22, and a block 38 is mounted in said guideway, a clamp 39 being shown as

surrounding the grade bar and guideway, and provided with a thumb screw 40, so that the block 38 may be secured in the guideway in any desired position. The block 38 carries a pin or screw 41 upon which one end of a link 42 is swiveled, the opposite end of such link being swiveled on a pin 43 mounted on the cutter head carriage. The link 42 thus serves to transmit motion from the cutter head carriage to the model-wheel carriage, the motion transmitted being greater or less according as the position of the pin 41 mounted on the block 38 is above or below the level of the pin 22 on which the grade bar is fulcrumed.

Mounted on the grade bar is a bracket 44 which carries a plate 45 having a heel rest 46 against which the heel of the model can be rested. The plate 45 also has a slideway 47 in which is mounted a slide 48 carrying a toe plate 49 that can be brought to bear on the toe of the model. As shown in Fig. 2, the slide 48 is provided with a spring 50 whose ends bear on the plate 45, so as to afford friction to tend to keep the slide in any position in which it is left. A cylinder 51 is mounted on a shaft 52 journaled in bearings on the bracket 44, and plate 45, a hand wheel 53 being provided on said shaft for the purpose of turning the cylinder. The cylinder is provided with a chart, which consists of a series of curved lines 54 that are arranged in fanlike formation, and a line 55 which would be straight if the chart were developed into flat formation instead of shaped around the cylinder. The block 38 or the pin 41 carries a pointer 56 which is adapted to be set to any of the lines 54 by shifting the block 38, and the toe plate 48 carries a pointer 57 which is arranged directly above the pointer 56 and is adapted to be set the length of the model away from the heel plate 46, and when such pointer is thus set, the model line 55 of the chart is intended to be turned until it touches the end of the pointer 57.

In using my grading mechanism and chart in the illustrated embodiment, the toe plate 32 is adjusted to a position the exact length of the model away from the heel plate 35, as by placing the model on the shelf 34 with its heel resting against the heel plate 35, and turning the screw shaft. The mechanism is so proportioned that when the toe plate 32 is in the described position, the pin 24 is vertically under the position which the center of the model occupies when the model is supported in the swinging frame upon the model heel and toe dogs. As the pitch of the thread 30^a is only one-half that of the thread 33, when the toe plate 32 is moved to accommodate a longer or shorter model, the pin 24 is always moved just one-half as much, and thus the pin 24 is always vertically under the center of any model

mounted on the model toe and heel dogs when the toe plate 32 is the length of that model away from the heel plate 34.

The manner in which the chart is calculated is as follows:

Assuming the chart to be formed upon a sheet of flexible material adapted to be shaped around the cylinder, I desire to form upon the sheet a series of points in a straight line, such as the series 58 to 72 formed in a straight line parallel to the axis of the cylinder, said points being so positioned that when the pointer 56 is set to the proper one of the said points, a last can be produced which is exactly the corresponding number 80 of sizes longer or shorter than the model last. Such a series of points will be differently spaced for each different length of model, and I wish to provide series of points for every length of model and a means for indicating which series of points corresponds to a given length of model. I have therefore provided the straight diagonal model line 55 to cause the series of points corresponding to a given model length to intersect the 90 said line at a point on said line opposite the pointer 57 when the latter is a vertical distance above the heel plate 46 equal to the length of the model and registered with said pointer when the series of points is rotated 95 around a vertical axis into collinearity with the pointers 56 and 57. Of course, the model line could be placed at a distance above or below from the position shown, so long as is were parallel to the position shown, and the pointer 57 were correspondingly placed. When so arranged and calculated for models of all lengths, the points relating to the same size grade form the respective curved, fanlike lines 54 which I have described, each 100 line being the locus of a set of size grade points, and the intersection of the curves by a vertical straight line forming a grading scale for a model of the corresponding length. When the new last is to be the same 110 length as the model, the motion transmitted from the cutter carriage to the model carriage must be unity, which is obtained when the pin 41 of the connecting bar 42 is at the level of the fulcrum pin 22 of the grade 115 bar, this being true no matter what the length of model used may be. Therefore, there will be a line which I shall call the "model" line 73, which will be straight and perpendicular to the axis of the cylinder. 120

In Fig. 10, I have shown diagrammatically the positions of the grade bar, the pivot pin 24 at the lower end of the grade bar, the fulcrum pin 22 by which the grade bar is swiveled on the model carriage, and 125 the pin 41 swiveling the connecting rod 42 upon the block 38, which is adjustable in the slideway 37 on the grade bar, these pins and the grade bar being shown in three positions, in one of which the model wheel is 130

at the extreme left-hand end of the model, in another of which the model wheel is at the extreme right-hand end of the model, and the third position in which the model wheel is at the center of the model. In the latter position the grade bar will always be vertical because, as before explained, the pin 24 is always vertically under the center of the model when the latter is mounted on the model live and dead centers. In the present machine, the distance A—B will always be the same no matter what the length of the model may be. The distance C—D will be greater or less, according as the new last is to be longer or shorter than the model to a greater or less extent, the line 41—41 being above the line 22—22 when the new last is to be longer than the model, and the line 41—41 being below the line 22—22 when the new last is shorter than the model. The rectilinear distance D—F will always be equal to the length of the new last, and the distance C—G always equal to the length of the model. Having, therefore, similar right-angle triangles ABC and AE'D, the distance C—D can easily be calculated for any length of model, and these distances give the vertical distance of any point of the series of points 58—72 above or below the model line 73.

Such a chart as I have is in effect a universal scale and will enable the making of a new last which is a given number of inches or sizes longer than the model last, no matter what the length of the model last may be. This has heretofore been impossible of easy and simple accomplishment with the type of grading mechanism I have shown, since the operative had to experiment with various adjustments of the grading mechanism until he could get one that would produce the desired addition or subtraction of sizes or half sizes to or from the length of the model last.

The change in angularity of the connecting rod 42, due to adjustments of the block 38, and due to the swinging of the grade bar, would render the calculation of such a chart as I have described a difficult matter, if it were not for the fact that the described arrangement always sets the lower fulcrum pin 24 vertically below the longitudinal center of the last, and thus the extreme left-hand and right-hand positions which the grade bar assumes are symmetrical to the vertical central position, and the angularity of the connecting rod 42 is therefore the same for those two extreme positions, and being the same can be disregarded.

As my chart is mounted on the grade bar 6 and travels with it, the pointer 56 is never separated from it in any position of the grade bar (as it would be, for instance, if the chart were mounted on the frame of the machine in position to be alongside the

grade bar when the grade bar is in its extreme left-hand position). It results that the operative can always see the position of the pointer on the chart at any time, and tell what size of last the lathe is set to produce. It also eliminates any possibility of error due to the pointer 56 not reaching its proper line of movement on the chart, as would be the case if the scale were stationary and the grade bar were not moved fully into position against it.

The pointer is preferably so mounted on the pin 41 that it does not have any turning movement with the connecting rod, as it would have if it were mounted on the connecting rod.

I have shown stops 74 and 75 to position the carriages always in the same position at the left hand end of their travel, so that they will always be in the same position when the grading mechanism is set, and so the knob or stub on the next last shall always be formed of a definite length and that length the shortest possible consistent with properly holding the heel end of such last. I also preferably form the connecting rod in two parts held together by a clamp 76 so that the carriages can always be positioned against the stops 74 and 75, as stated.

I claim:

1. In a last lathe, the combination of a model carriage, a cutter carriage, and grading mechanism for transmitting motion from one of said carriages to the other, comprising a lever mounted on a pin carried by the model carriage, and on a pin carried on the frame, a connecting rod pivoted to the cutter carriage and adjustably connected with said lever, and means for adjusting the pin on the frame to a position vertically central below the model, said means comprising a slide carrying said pin and mounted in a slideway parallel to the line of movement of said carriages, and a universal scale for setting the grading mechanism to grade from models of all lengths.

2. In a last lathe, the combination of a model carriage, a cutter carriage, and grading mechanism for transmitting motion from one of said carriages to the other, comprising a lever pivoted on the model carriage, and on the frame, a connecting rod pivoted to the cutter carriage and adjustably connected with said lever, and means for adjusting the pivot on the frame to a position vertically central below the model, said means comprising a part adapted to be adjusted according to the length of the model, and connections between said part and said pivot, such that said pivot is moved parallel to the line of movement of said carriages one-half the distance of movement of said part.

3. In a last lathe, the combination of a model carriage, a cutter carriage, and grad-

- ing mechanism for transmitting motion from one of said carriages to the other, comprising a lever pivoted on the model carriage, and on the frame, a connecting rod pivoted to the cutter carriage and adjustably connected with said lever, and means for adjusting the pivot on the frame to a position vertically central below the model, said means comprising a slideway parallel to the line of movement of said carriages, having two slides mounted therein, one of which carries said pivot, means for indicating positions of the other of said slides corresponding to the length of the model, and means for transmitting motion from the other of said slides to said pivot-carrying slide, such that said pivot-carrying slide will be moved one-half as much as said second mentioned slide.
4. In a last lathe, the combination of a model carriage, a cutter carriage, and grading mechanism for transmitting motion from one of said carriages to the other, comprising a lever pivoted on the model carriage, and on the frame, a connecting rod pivoted to the cutter carriage and adjustably connected with said lever, and means for adjusting the pivot on the frame to a position vertically central below the model, said means comprising a slideway parallel to the line of movement of said carriages, a slide mounted in said slideway, and carrying said pivot, a slide mounted in said slideway for indicating the length of the model, and a screw shaft having threads adapted to engage said slides, the thread of the pivot slide being one-half the pitch of the other thread.
5. In a last lathe, the combination of a model carriage, a cutter carriage, and grading mechanism for transmitting motion from one of said carriages to the other, comprising a lever pivoted on the model carriage, and on the frame, a connecting rod pivoted to the cutter carriage and adjustably connected with said lever, and means for adjusting the pivot on the frame to a position vertically central below the model, said means comprising a slideway parallel to the line of movement of said carriages, and having two slides mounted therein, one slide carrying said pivot, and the other slide carrying a part adapted to be engaged by an end of the model, said slideway having an abutment adapted to be engaged by the other end of the model, and the screw shaft engaging said slides by screw threads, the thread of the pivot carrying slide being one-half the pitch of the other thread.
6. In a last lathe, the combination of a model carriage, a cutter carriage, grading mechanism adapted to transmit graded motion from one of said carriages to the other and comprising a part adjustable to grade said motion, and a series of scales graduated

to produce the grades corresponding to different model lengths adapted to be used in setting said part, said series of scales being mounted upon said grading mechanism, so as to always be in operative relation to said part.

7. In a last lathe, the combination of a model carriage, a cutter carriage, grading mechanism adapted to transmit graded motion from one of said carriages to the other, and comprising a connecting rod and a universal scale, and means for causing the extreme positions of the connecting rod to have a common degree of angularity determined by the length of travel of the model carriage.

8. In a last lathe, the combination of a model carriage, a cutter carriage, grading mechanism adapted to transmit graded motion from one of said carriages to the other, and comprising a connecting rod, a universal scale by which said mechanism is adapted to be set to grade from any model, and means for causing the extreme positions of the connecting rod to balance each other, irrespective of the length of the model.

9. In a last lathe, the combination of a model carriage, a cutter carriage, grading mechanism adapted to transmit graded motion from one of said carriages to the other, and comprising a connecting rod, a universal scale by which said grading mechanism is adapted to be set to grade from any model, and means adapted to render the positions of the connecting rod, when the model carriage is at the extremities of the model, symmetrical irrespective of the model length.

10. In a last lathe, the combination of a model carriage, a cutter carriage, grading mechanism adapted to transmit graded motion from one of said carriages to the other, and comprising a connecting rod, a universal scale by which said grading mechanism is adapted to be set to grade from any model, and means adapted to render the positions of the connecting rod, when the model carriage is at the extremities of the model, of the same degree of angularity dependent upon the length of travel of the model carriage.

11. In a last lathe, the combination of a model carriage, a cutter carriage, grading mechanism adapted to transmit graded motion from one of said carriages to the other, and comprising a connecting rod, a universal scale by which said grading mechanism is adapted to be set to grade from a model of any length, and means adapted to render the positions of the connecting rod, when the model carriage is at the extremities of the model, such that the angularities of said connecting rod shall cancel each other irrespective of the model length.

12. In a last lathe, the combination of a

- model carriage, a cutter carriage, grading mechanism adapted to transmit graded motion from one of said carriages to the other, and comprising a connecting rod, a universal scale by which said grading mechanism is adapted to be set, and means adapted to render the positions of the connecting rod to grade from any model, when the model carriage is at the extremities of the model, such that the angularities of said connecting rod shall cancel each other, said means comprising devices whereby the axis of the crank for said connecting rod may be fulcrumed, so as, in effect, to be central of the length of the model.
13. In a last lathe, the combination of a model carriage, a cutter carriage, grading mechanism adapted to transmit graded motion from one of said carriages to the other, and comprising a part adjustable to grade said motion, and a series of scales graduated to produce the grades corresponding to different model lengths having a fixed relation to the path of movement of said part, so as to always be in operative relation to said part.
14. In a last lathe, the combination of a model carriage, a cutter carriage, grading mechanism adapted to transmit graded motion from one of said carriages to the other, and comprising a part adjustable to grade said motion, and a series of scales adapted to be used in setting said part, said series of scales being mounted upon a cylinder, said cylinder being mounted upon said grading mechanism so as to always be in operative relation to said part.
15. In a last lathe, the combination of a model carriage, a cutter carriage, grading mechanism adapted to transmit graded motion from one of said carriages to the other, and comprising a part adjustable to grade said motion, and a series of scales adapted to be used in setting said part, said series of scales being mounted upon a cylinder, said cylinder being mounted upon said grading mechanism so as to always be in operative relation to said part, said series of scales comprising a series of lines whose intersections with the path of movement of said part in a given position of said scales, indicate positions of said part to obtain predetermined variations in length of a given model.
16. In a last lathe, the combination of a model carriage, a cutter carriage, grading mechanism adapted to transmit graded motion from one of said carriages to the other, and comprising a part adjustable to grade said motion, a series of scales adapted to be used in setting said part, said series of scales being mounted upon a cylinder, said cylinder being mounted upon said grading mechanism so as to always be in operative relation to said part, said series of scales

comprising a series of lines whose intersections with the path of movement of said part in a given position of said scales, indicate positions of said part to obtain predetermined variations in length of a given model, and means for indicating the relative positions of said lines and part for a given length of model.

17. In a last lathe, the combination of a model carriage, a cutter carriage, grading mechanism adapted to transmit graded motion from one of said carriages to the other, and comprising a part adjustable to grade said motion, a series of scales adapted to be used in setting said part, said series of scales being mounted upon a cylinder, said cylinder being mounted upon said grading mechanism so as to always be in operative relation to said part, said series of scales comprising a series of lines whose intersections with the path of movement of said part in a given position of said scales, indicate positions of said part to obtain predetermined variations in length of a given model, and means for indicating the relative positions of said lines and part for a given length of model, said means comprising a line at an angle to said series of lines.

18. In a last lathe, the combination of a model carriage, a cutter carriage, grading mechanism adapted to transmit graded motion from one of said carriages to the other, and comprising a part adjustable to grade said motion, a series of scales adapted to be used in setting said part, said series of scales being mounted upon a cylinder, said cylinder being mounted upon said grading mechanism so as to always be in operative relation to said part, said series of scales comprising a series of lines whose intersections with the path of movement of said part in a given position of said scales, indicate positions of said part to obtain predetermined variations in length of a given model, means for indicating the relative positions of said lines and part for a given length of model, said means comprising a line at an angle to said series of lines, and a pointer for indicating the proper position of said angled line for a given model.

19. In a last lathe, the combination of a model carriage, a cutter carriage, grading mechanism adapted to transmit graded motion from one of said carriages to the other, and comprising a part adjustable to grade said motion, a series of scales adapted to be used in setting said part, said series of scales being mounted upon a cylinder, said cylinder being mounted upon said grading mechanism so as to always be in operative relation to said part, said series of scales comprising a series of lines whose intersections with the path of movement of said part in a given position of said scales, indicate positions of said part to obtain predetermined variations in length of a given model, and means for indicating the relative positions of said lines and part for a given length of model, said means comprising a line at an angle to said series of lines, and a pointer for indicating the proper position of said angled line for a given model.

- terminated variations in length of a given model, means for indicating the relative positions of said lines and part for a given length of model, said means comprising a line at an angle to said series of lines, a pointer for indicating the proper position of said diagonal line for a given model, and means for positioning said pointer according to the length of the model.
10. 20. In a last lathe, the combination of a model carriage, a cutter carriage, grading mechanism adapted to transmit graded motion from one of said carriages to the other, and comprising a part adjustable to grade said motion, a series of scales adapted to be used in setting said part, said series of scales being mounted upon a cylinder, said cylinder being mounted upon said grading mechanism so as to always be in operative relation to said part, said series of scales comprising a series of lines whose intersections with the path of movement of said part in a given position of said scales, indicate positions of said part to obtain predetermined variations in length of a given model, means for indicating the relative positions of said lines and part for a given length of model, said means comprising a line at an angle to said series of lines, a pointer for indicating the proper position of said angled line for a given model, and means for positioning said pointer according to the length of the model, said means for positioning said pointer comprising an abutment for one extremity of the model, and a slide carrying said pointer and movable toward and from said abutment.
25. 21. In a last lathe, the combination of a model carriage, a cutter carriage, grading mechanism adapted to transmit graded motion from one of said carriages to the other, comprising a lever fulcrumed on the frame, and adapted to be swung by said model carriage, a connecting rod pivoted to said cutter carriage, and adjustably connected with said lever, means for adjusting the fulcrum of said lever to a position vertically central below the model, a series of scales carried by said lever for adjusting said connecting rod on said lever, said series of scales being mounted on a cylinder parallel with said lever, and comprising a line perpendicular to the axis of said cylinder for positioning said connecting rod in neutral position, a fan-shaped series of lines approaching parallelism to said line at one extremity thereof, and a model line for indicating the position of said cylinder for a particular model, and a pointer adapted to be positioned according to the length of the model, for indicating the proper position of said model line.
30. 24. A scale for a last turning lathe comprising a base line corresponding to the model size, and curves corresponding to different styles of other sizes of lasts, said curves each consisting of a series of points at distances from said base line proportional to the difference in size plus an extension determined by the style of last and also proportional to a leverage of the grading mechanism which leverage varies with the length of the model.
35. 25. A scale for a last turning lathe comprising a base line corresponding to the model size, curves corresponding to different styles of other sizes of lasts, said curves each consisting of a series of points at distances from said base line proportional to the difference in size plus an extension determined by the style of last and also proportional to a leverage of the grading mechanism, which leverage varies with the length of the model, said scale also having a reference line comprising points respectively having a definite relation to said first mentioned points and spaced from said base line distances proportional respectively to

the lengths of the corresponding styles of lasts of the same size.

26. The method of determining the position of points upon a grading scale corresponding to different sizes of a given model of last, which comprises establishing on said scale a base line corresponding to the model size, and locating a scale point for another size at a distance from said base line, proportional to the difference in size plus an extension determined by the style of the last.

27. The method of determining the position of points upon a grading scale corresponding to different sizes of a given model of last, which comprises establishing on said scale a base line corresponding to the model size, and locating a curve corresponding to different styles of another size of last, 15 by progressively plotting a series of points at a distance from said base line proportional to the difference in size plus extensions respectively determined by the styles of last corresponding to the points.

28. The method of determining the position of points upon a grading scale corresponding to different sizes of a given model of last, which comprises establishing on said scale a base line corresponding to the model size, locating a scale point for another size at a distance from said base line, proportional to the difference in size plus an extension determined by the style of the last, and plotting on the scale a reference point having a definite relation to said first mentioned point and spaced from said base line a distance proportional to the length of the extension for the corresponding style of last.

29. The method of determining the position of points upon a grading scale corresponding to different sizes of a given model of last, which comprises establishing on said scale a base line corresponding to the model size, locating a curve corresponding to different styles of another size of last, by progressively plotting a series of points at a distance from said base line proportional to the difference in size plus extensions respectively determined by the styles of last corresponding to the points, and plotting on the scale a reference line comprising points respectively having a definite relation to said first mentioned points and spaced from said base line distances proportional respectively to the lengths of the corresponding styles of last.

30. The method of determining the position of points upon a grading scale corresponding to different sizes of a given model of last, which comprises establishing on said scale a base line corresponding to the model size, locating a curve corresponding to different styles of another size of last, by progressively plotting a series of points at a

distance from said base line proportional to the difference in size plus extensions respectively determined by the styles of last corresponding to the points, and plotting on the scale a reference line comprising points respectively having a definite relation to said first mentioned points and spaced from said base line distances proportional respectively to the lengths of the corresponding styles of lasts of the same size.

31. In a machine of the class described, a carriage on the model side, a carriage on the work side, and grading mechanism for effecting a relative movement between them comprising a part adjustable to grade said movement and a universal chart for setting said part, mounted on the grading mechanism in such manner as always to be in operative relation to said part.

32. In a machine of the class described, a carriage on the model side, a carriage on the work side, and grading mechanism for effecting a relative movement between them comprising a part adjustable to grade said movement and a universal chart for setting said part, mounted on the grading mechanism in such manner as always to be in operative relation to said part, said chart showing the locus of the setting points for said part for a certain grade from models of all 95 lengths.

33. In a machine of the class described, a carriage on the model side, a carriage on the work side, and grading mechanism for effecting a relative movement between them comprising a part adjustable to grade said movement and a universal chart for setting said part, mounted on the grading mechanism in such manner as always to be in operative relation to said chart, said chart containing the loci of the setting points of said part, relating respectively to the different grades from models of all lengths.

34. In a machine of the class described, a carriage on the model side, a carriage on the work side, and grading mechanism for effecting a relative movement between them comprising a part adjustable to grade said movement and a universal chart for setting said part, mounted on the grading mechanism in such manner as always to be in operative relation to said part, said chart containing a curve whose ordinates measured from a line of reference correspond to a continuous series of settings of said part corresponding to a certain grade from a series of models of continuously varying length.

35. In a machine of the class described, a carriage on the model side, a carriage on the work side, and grading mechanism for effecting a relative movement between them comprising a part adjustable to grade said movement and a universal chart for setting said part mounted on the grading mechanism in such manner as always to be in oper- 130

ative relation to said part, said chart showing the locus for the setting points for said part for a certain grade from models of all lengths, a pointer constructed and arranged 5 to be moved to measure the length of the model and a point on every ordinate of the said curve arranged for coöperation with the

pointer to bring the proper point of the curve into the path of adjustment of the said part.

10

In testimony that I claim the foregoing I have hereunto set my hand.

EDWIN J. PRINDLE.
